Des. 230,808
Patented Mar. 19, 1974

230,808

DISPLAY BOARD FOR PHOTOGRAPHS OR THE LIKE

Thomas G. Edwards, 855 3rd St.,
Santa Monica, Calif. 90403

Filed Sept. 21, 1972, Ser. No. 290,783

Term of patent 14 years

Int. Cl. D6—07

U.S. Cl. D6—234

FIG. 1

FIG. 2

FIG. 3

FIG. 1 is a perspective view of a display board for photographs or the like showing my new design;

FIG. 2 is a front elevational view; and

FIG. 3 is a perspective view taken from below.

I claim:

The ornamental design for a display board for photographs or the like, substantially as shown.
